UNITED STATES PATENT OFFICE.

JOHN B. BATES, OF ANNISTON, ALABAMA, ASSIGNOR OF ONE-HALF TO W. L. MOSS, OF ANNISTON, ALABAMA.

MOLDING APPARATUS.

1,187,027.

Specification of Letters Patent. Patented June 13, 1916.

Application filed January 5, 1916. Serial No. 70,504.

To all whom it may concern:

Be it known that I, JOHN B. BATES, a citizen of the United States, residing at Anniston, in the county of Calhoun and State of Alabama, have invented certain new and useful Improvements in Molding Apparatus, of which the following is a specification, reference being had to the accompanying drawings.

10 This invention relates to certain improvements in molding apparatus and has relation more particularly to a device of this general character wherein a flask is employed and it is an object of the invention to provide an apparatus of this general character having novel and improved means whereby the flask may be applied to or removed from operative position with convenience and facility.

20 It is also an object of the invention to provide a device of this general character wherein the flasks when removed may be maintained in superposed relation whereby a plurality of flasks may be employed at one 25 pouring of metal.

The invention consists in the details of construction and in the combination and arrangement of the several parts of my improved molding apparatus whereby certain important advantages are attained and the device is rendered simpler, less expensive and otherwise more convenient and advantageous for use, all as will be herein-after more fully set forth.

35 The novel features of the invention will be carefully defined in the appended claims.

In order that my invention may be the better understood, I will now proceed to describe the same with reference to the accompanying drawing, wherein—

Figure 1 is a view in top plan of a molding apparatus constructed in accordance with an embodiment of my invention; Fig. 2 is a vertical sectional view taken longitudinally through the device as disclosed in Fig. 1; Fig. 3 is a horizontal sectional view taken through the device as herein embodied; Fig. 4 is a vertical sectional view taken transversely through my improved 45 molding apparatus as herein included; Fig. 5 is a view in elevation of the side face of the hinged stripping plate as herein embodied; Fig. 6 is a horizontal sectional view taken through the device as herein disclosed

with the flask removed and the movable parts in an open position; and Fig. 7 is a view in perspective, detached, of the flask herein embodied.

As disclosed in the accompanying drawings, 1 denotes the bottom of a container of predetermined configuration but herein disclosed as rectangular in plan and having extending upwardly adjacent its opposite ends the side walls or plates 2, and said side plates adjacent their opposite end have disposed across their outer faces the ribs 3, extending beyond the opposite vertical edges of the side plates or walls, the rearwardly extending portion being reinforced by the ribs 4 overlying the outer face of the rear or fixed stripping plate 5.

The stripping plate 5 as herein embodied, is provided with the elongated vertically disposed slots of predetermined configuration, through which the patterns P carried by the inner face of the back plate 6 are adapted to extend, said patterns being herein disclosed as of a type to produce sash weights.

The back plate 6 as herein disclosed, is provided at its upper and lower ends with the oppositely directed lugs 7 adapted to underlie the rearwardly extended portions of the ribs 3 and pivotally engaged as at 8, with one set of vertically aligned ribs 3, while the second set of ribs or more particularly the rearward extensions thereof are provided with perforations 9 through which the pins 10 may be disposed to maintain the back plate in closed adjustment.

11 denotes a second stripping plate provided along one vertical margin with the extensions 12 pivotally engaged with the forward extensions of the adjacent ribs 3, while the opposite or free vertical edge of the second stripping plate 11 is provided with extensions 14 adapted to extend across the forward extensions of the ribs 3 at the side opposite to the hinged connection of the stripping plate 11, and the outer extremities of said last named extensions of the ribs 3 are provided with the perforations 15, through which the locking pins 16 are directed for a purpose which is believed to be self-evident. The pins 16 also coact with the extensions 17 carried by the adjacent vertical marginal portion of the front 18, the opposite vertical marginal portion of

the front being provided with the extensions 19 pivotally engaged with the forward extensions of the first mentioned ribs 3.

5 The second stripping plate 11 is also provided with the elongated vertically disposed slots or openings 20 through which extend the patterns P^1 carried by the inner face of the front 18.

10 It is also to be observed that the inner face of the second stripping plate 11 is provided with a pattern P^2 whereby means is provided for the requisite pouring of the metal.

15 F denotes the flask which, as herein disclosed, includes the bottom plate 21, the upper standing side plates 22 and the upper transverse tie plates 23, whereby it is to be noted that the upper end of the flask F is open for the proper application of the sand. At this time it may be well to state that my improved apparatus may be employed in connection with any preferred style of jarring machine.

20 One of the side plates adjacent its opposite ends and at its vertical marginal portions is provided with outstanding lugs 24, one vertical set of lugs being provided with the opening or perforation 25 to receive the inwardly disposed pins 26 carried by the stripping plate 5, while the second vertical set of lugs 24 is provided with the outstanding pins 27 for a purpose to be hereinafter more particularly referred to. Both of the side plates 22 are provided at substantially their transverse centers and intermediate 35 their length with the elongated ribs 28 which serve as the medium for the proper manipulation of the flask when removed.

25 In the operation of my improved molding apparatus, after the same has been jarred sufficient to cause the proper set of the sand, the front 18 is adjusted into open position and then the back plate 6 is adjusted into open position. The second stripping plate 11 is then swung open and the flask F drawn from within the molding apparatus and laid down flat with the pins 26 extending upwardly so that a second flask may be superimposed upon the first flask with the pins 26 of the lower flask directed through 40 the openings or perforations 25 of a second flask. In practice it has been found that the flasks may be five or six deep, whereby an increased output may be had at a single pouring.

45 From the foregoing description, it is thought to be obvious that a molding apparatus constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit

thereof and for this reason I do not wish to be understood as limiting myself to the precise arrangement and formation of the several parts herein shown in carrying out my invention in practice.

7 I claim:

1. A molding apparatus consisting of a container having its front and back open, swinging closure members for the front and back, said members being provided on their inner faces with patterns, a fixed stripping plate overlying the back of the container and provided with an opening through which the pattern of the back closure member extends, a hinged stripping plate overlying the front of the container and arranged inwardly of the front closure member, and a flask insertible within the container and having its front and rear faces open.

85 2. A molding apparatus consisting of a container having its front and back open, swinging closure members for the front and back, said members being provided on their inner faces with patterns, a fixed stripping plate overlying the back of the container and provided with an opening through which the pattern of the back closure member extends, a hinged stripping plate overlying the front of the container and arranged inwardly of the front closure member, and a flask insertible within the container and having its front and rear faces open,

90 3. A molding apparatus consisting of a container having its front and back open, swinging closure members for the front and back, said members being provided on their inner faces with patterns, a fixed stripping plate overlying the back of the container and provided with an opening through which the pattern of the back closure member extends, a hinged stripping member overlying the front of the container and arranged inwardly of the front closure member, a flask insertible within the container and having its front and rear faces open, lugs projecting outwardly from a side wall of the flask, certain of said lugs being perforated, and pins carried by the remainder of said lugs.

95 4. A molding apparatus consisting of a container having its front and back open, swinging closure members for the front and back, said members being provided on their inner faces with patterns, a fixed stripping plate overlying the back of the container and provided with an opening through which the pattern of the back closure member extends, a hinged stripping member overlying the front of the container and arranged inwardly of the front closure member, a flask insertible within the container and having its front and rear faces open, lugs projecting outwardly from a side wall of the flask.

wall of the flask, one of said lugs being perforated, and a pin carried by a second lug, the first named stripping plate being provided with a pin adapted to extend through 5 the perforation in the lug of the flask.

5. A molding apparatus consisting of a container having its front and back open, swinging closure members for the front and back, said members being provided on their 10 inner faces with patterns, a fixed stripping plate overlying the back of the apparatus and provided with an opening through which the pattern of the back closure member extends, and a hinged stripping member 15 overlying the front of the apparatus and arranged inwardly of the front closure member.

6. A molding apparatus consisting of a container having one of its faces open, a 20 swinging closure member for said open face, said member being provided on its inner face with a pattern, and a stripping plate overlying the open face of the container and provided with an opening through 25 which the pattern of the closure member extends.

7. A molding apparatus consisting of a container having one of its faces open, a swinging closure member for said open face, 30 said member being provided on its inner face with a pattern, and a stripping plate overlying the open face of the container and provided with an opening through which

the pattern of the closure member extends, said stripping plate being capable of movement. 35

8. A molding apparatus consisting of a container having opposite faces open, movable closure members for said open faces, said members being provided with patterns 40 adapted to extend within the container when said closure members are in closed position, and stripping plates overlying the open faces of the container and provided with openings through which the patterns of the 45 closure members extend.

9. A molding apparatus consisting of a container having openings in opposite walls, swinging closure members carried by the 50 container and overlying the walls provided with the openings, and patterns carried by the inner faces of the closure members and extending within the container through the openings in the walls.

10. A molding apparatus including a container and a flask removably insertible therein, said flask having lugs projecting outwardly from a wall thereof, one of said lugs being perforated, and a pin carried by a 55 second lug. 60

In testimony whereof I hereunto affix my signature in the presence of two witnesses.

JOHN B. BATES.
